UNITED STATES PATENT OFFICE

AUBREY D. DAVID, OF CHICAGO, ILLINOIS, ASSIGNOR TO THE UNIVERSAL OIL PRODUCTS COMPANY, OF CHICAGO, ILLINOIS, A CORPORATION OF SOUTH DAKOTA

PROCESS FOR THE DESTRUCTIVE DISTILLATION OF PETROLEUM OIL

Application filed February 14, 1923. Serial No. 619,037.

This invention relates to improvements in a process for distilling petroleum oil and refers more particularly to the pressure distillation of oils to produce relatively light 5 hydrocarbons having the characteristics of gasoline.

Among the objects of the invention are to provide a process in which the deposited free carbon particles separated out during 10 the conversion of the oil are removed from the conversion stage by a flotation medium and the carbon particles eliminated therefrom in a separate oxidizing stage; to provide a process whereby the oil may be 15 treated over a considerable period of time due to the fact that the carbon accumulation is materially reduced and the necessity for shutting down the apparatus for cleaning is materially lessened, and to provide an 20 apparatus for carrying out this process.

The single figure is a diagrammatic side elevational view of the apparatus. At 1 is shown a side-fired furnace in which are mounted the heating coil tubes 2. At 3 is 25 shown an enlarged reacting or conversion chamber which is connected by a vapor line 4 to a dephlegmator 5. The dephlegmator, in turn, is connected by a line 6 to a water condenser 7, the discharge end of which is 30 connected by a pipe 8 to a receiving tank 9.

A liquid draw-off line 10 from the expansion chamber communicates with a combustion chamber 11 which has a discharge line 12 communicating with the suction side 35 of the pump 13, the latter being connected through a discharge line 14 back to the chamber 3 so that a continual circulation may be maintained between the two chambers.

40 The oil to be treated is introduced from any convenient source through the pipe 15 which is looped through the top of the combustion chamber 11 to extract heat therefrom and to pre-heat the oil traveling 45 through the charging line. The pre-heated charging stock is directed through the line 15 which is connected to the heating coils 2 by means of a line 16. The oil after being heated to a conversion temperature in the 50 heating coils 2 is discharged through trans-

fer line 17 controlled by a valve 18 into the expansion or vaporizing chamber 3. In the bottom of the expansion chamber is maintained a body of molten lead as shown at 19. The oil body is permitted to collect 55 above this molten lead body, the level being controlled by means of a draw-off line 20 controlled by a valve 21 and tricocks 22. The vapors evolved during the conversion of the oil pass off through the vapor line 4 and 60 are subjected to dephlegmating and condensing actions in the separate stages 5 and 7. The condensed vapors are collected as liquid distillate in the receiving tank 9 which is equipped with a pressure relief 65 valve 23, pressure gauge 24, liquid level gauge 25, and liquid draw-off valve 26. The pressure on the system may be controlled by means of the pressure relief valve or differential pressure upon the different 70 stages maintained by the valves 18, 27, and 28 positioned between the different stages. A reflux condensate separated out in the dephlegmating stage may be returned 75 through the pipe 29 controlled by a valve 30 and recycled with the stock through the heating stage.

During the conversion of the oil in the expansion or vaporizing chamber 3 there will be separated out finely divided free 80 carbon particles which would normally accumulate in the expansion chamber. Some of this carbon would remain in suspension in the unvaporized oil and be carried off in the residual products withdrawn from the 85 chamber, while a portion of the carbon would collect in a relatively solid sludgy or coky mass in the bottom of the chamber. To prevent this objectionable carbon accumulation, the free carbon particles which 90 are rained from the oil body during its conversion are collected on the surface of the flotation medium or molten lead which is maintained in the bottom of the chamber. This molten lead has a heavier specific gravity than the carbon and for this reason the 95 free carbon will remain upon its surface. This flotation medium is withdrawn from the chamber 3 through the line 10 and valve interposed therein and circulated through 100

a combustion chamber 11, into which is introduced a gas such as air through a pipe 31. At the same time through the pipe 32 is withdrawn the gaseous constituents formed by the combustion of the carbonaceous particles with the air introduced through the line 31. Valves 33 and 34 are interposed in these lines to regulate the introduction and withdrawal of the gases. It is essential that the introduction of air be accurately controlled to prevent too active an accumulation of gas in the combustion chamber. The functioning of the chamber is such that the carbon floating upon the molten lead is burned off and is expelled from the chamber through the line 32 as carbon monoxide or carbon dioxide. The molten lead is withdrawn from the combustion chamber through the line 12 and is circulated by means of the pump 13 back into the chamber 3 through the line 14. Valves are interposed in the suction and discharge lines of the pump for regulating the flow of the liquid. The vaporizing and combustion chambers are preferably operated at substantially the same pressure, the differential pressure conditions which may be maintained therein being only sufficient to assure the circulation of the flotation medium from one chamber to the other and such differential pressure as may be caused by the circulating pump 13.

The advantage of the apparatus is readily appreciated, as the carbon accumulation is practically eliminated, permitting the apparatus to be operated over a considerable period of time without the necessity of shutting down for cleaning the carbon from the expansion or conversion stage.

40 I claim as my invention:

1. A process for cracking petroleum oil consisting in heating the oil to a conversion temperature, permitting the oil to vaporize while maintaining it in a substantial body above a flotation medium in an enlarged expansion zone, drawing off the carbon separated out during conversion by withdrawing the flotation medium from the expansion zone, removing the carbon from the flotation medium by oxidation and recycling the medium back to the expansion stage.

2. A process for cracking petroleum oil consisting in heating the oil to a conversion temperature, permitting the conversion to take place in an enlarged expansion chamber containing a molten flotation medium having a specific gravity in excess of the free carbon particles, removing the carbon from the system by continuously withdrawing the flotation medium from the expansion chamber, subjecting it in a separate stage to an oxidizing action and continuously recycling the flotation medium devoid of the carbon back to the expansion chamber.

3. A process for cracking petroleum oil consisting in heating the oil in a relatively small stream in a heating zone, passing the oil to an enlarged expansion zone containing a flotation medium and there collecting it in a substantial body, dephlegmating and condensing the evolved vapors and maintaining a substantial pressure on the oil during treatment, removing the free carbon separated from the oil during conversion by withdrawing the flotation medium, having the carbon supported thereon and subjecting it to an oxidizing action in a separate combustion zone, recycling the carbon free medium back to the expansion zone.

4. A process of converting heavier into lower hydrocarbons, consisting in continuously passing the oil through a heating zone wherein it is subjected to a cracking temperature, in discharging the products of conversion from said heating zone into an enlarged expansion chamber where substantial vaporization occurs and carbon is precipitated, in maintaining a supply of molten metal in said expansion chamber on the surface of which, said precipitated carbon is suspended, in continuously withdrawing molten metal and the suspended carbon from said expansion chamber and passing it to a combustion chamber wherein the carbon is oxidized, and in continuously recycling the molten metal free from carbon from said combustion chamber to said expansion chamber.

5. A process for treating oil in which combustible solids separate from the oil, comprising maintaining a body of heated oil in an enlarged chamber, wherein the combustible solids precipitate out of the oil, continuously removing the combustible solids precipitated out of the oil from such enlarged chamber, admitting the same to an oxidizing zone, wherein combustion thereof occurs, and imparting the heat given up by combustion of said combustible solids in said oxidizing zone to oil being supplied to the process, to preheat the same.
